CLAIM

The ornamental design for a thermostat device with low profile trim plate, as shown and described in the Figures.

DESCRIPTION

FIG. 1 is a perspective view of a thermostat device with a trim plate showing a new design for a thermostat device with a trim plate;

FIG. 2 is a front plan view thereof;

FIG. 3a is a top plan view thereof;

FIG. 3b is a bottom plan view thereof;

FIG. 4a is a side plan view thereof;

FIG. 4b is another side plan view thereof;

FIG. 5 is an exploded view of the thermostat and trim plate shown in FIG. 1;

FIG. 6 is a front plan view of the trim plate shown in FIG. 5;

FIG. 7 is a side plan view of the trim plate shown in FIG. 5;

FIG. 8 is a front plan of the thermostat shown in FIG. 5;

FIGS. 9a and 9b are side plan views of the thermostat shown in FIG. 5;

FIG. 10a is a top plan view of the thermostat shown in FIG. 5; and,

FIG. 10b is a bottom plan view of the thermostat shown in FIG. 5.
